(57) CLAIM

We claim the ornamental design for panel bed, as shown and described.

DESCRIPTION

FIG. 1 is a left front perspective view of a panel bed according to an embodiment of the invention.

FIG. 2 is a front elevational view of the headboard portion of a panel bed according to an embodiment of the invention.

FIG. 3 is a front elevational view of the footboard portion of a panel bed according to an embodiment of the invention.

FIG. 4 is a side elevational view of a panel bed according to an embodiment of the invention. The opposite side is a mirror image thereof; and,

FIG. 5 is a top plan view of a panel bed according to an embodiment of the invention.

The rear views of the headboard and footboard portions are not shown and form no part of the claimed design. The dashed lines represent environmental elements only and form no part of the claimed design.
